RADIO TELEGRAPH AND TELEPHONE TRANSMITTING SYSTEM

Application filed April 2, 1923, Serial No. 629,479. Renewed May 19, 1923.

This invention relates to improvements in the arrangement and connections of electrical apparatus at the transmitting station of a radio communication system; the object being to create and modulate electro-magnetic waves of a kind suitable for transmission to, and wherein the modulations may be detected and interpreted at, a distant receiving station. The invention embodies new means 10 of accomplishing the results mentioned.

It is to be noted that I have included in my improved arrangement of circuits, certain known circuits and combinations of electrical apparatus, in an elementary way, to 15 the extent that I have embodied therein, together with other known elementary circuits and devices, a circuit which includes two three electrode electron tubes (or their equivalent, one five electrode electron tube.)

20 It also embodies an inductance and capacitance, in parallel, connected in series with a local generator of electric current. All of which have been shown in my prior Patent Number 1,507,689, issued Sept. 9, 1924. I

25 depart, however, from previous use of these known circuits by combining them together, in association with other electrical apparatus, and in adjusting their constants, in a manner which converts energy, locally generated 30 in the form of an electric current, into energy in the form of electro-magnetic waves, wherein novel means are also provided for modulating the dimensions of such electro-magnetic waves to accord with modulations 35 in locally applied forces, as will be understood from the following description in connection with the accompanying drawings.

In carrying out the above objects I preferably employ a form of converter of electric 40 current embodying two three electrode electron valves, or their equivalent, each having a separate control member, usually that electrode termed the grid, but which may be any element of the valve which controls the conductivity of the valve, and provide, in connection with said electron valves, means for impressing electric potential differences between the respective control members of said 45 electron valves to modulate the converted 50 electric current.

In this description I shall designate as "triodes", three electrode electron tubes, each embodying an evacuated vessel containing a hot cathode, an anode in the form of a plate or concentric cylinder and another electrode 55 placed in a position with respect to the cathode and anode, such that variations in its electrical potential with respect to either of the other two electrodes will cause like variations in the electric current between 60 them. I shall designate the anode of each triode as the "plate", the cathode as the "filament" and the third electrode as the "grid."

In the drawings Figure 1 illustrates, diagrammatically, a form of my arrangement of the transmitting circuit and electrical apparatus at a radio communication station. Figure 2 represents a similar arrangement modified to permit the radiating part of the 70 circuit to be inductively coupled to the remainder of the circuit, instead of directly coupled as shown in Figure 1.

Like reference numerals designate like parts throughout the several views. 75

Referring particularly to Fig. 1, the numeral 1 represents the ordinary elevated part of an antenna, at a radio transmitting station, which is electrically connected in series, in the order given, with a switch 2, inductance coil 3, inductance coil 5, switch 4, condenser 6, to the ground, or counterpoise 7. The switches 2 and 4 are preferably mechanically actuated by a single control member, not shown, common to both of them and so adjusted that the active part of each of the coils 3 and 5 shall be of equal inductance. A variable condenser 8 is electrically connected in series between the switch 2 and the grid 13 of a triode 10. A variable condenser 9 is electrically connected in series between the switch 4 and the grid 13 of another triode 11. The plate 12 of the triode 10 is electrically connected to the switch 4. The plate 12 of the triode 11 is electrically connected to the 85 switch 2. 90

30 is the primary coil of an audio frequency transformer, having a core 29, of magnetic material, and a secondary coil 28. One terminal of the secondary coil 28 is electrici 100

cally connected to the grid 13 of the triode 10. The other terminal of coil 28 is electrically connected to the grid 13 of triode 11. One terminal of the secondary coil 28 is electrically connected to one terminal of a switch 40 the other terminal of which is electrically connected to one of the contacts of a key switch 39; the other contact of the key switch 39 is electrically connected to the remaining terminal of the secondary coil 28. The normal position of the key switch 39 is such that its contacts close the circuit with which they are associated. 31 represents a telephone transmitter, or a key actuated buzzer, or any device which may function in a similar manner. For the purposes of this description I shall refer to 31 as the "telephone", except as I may more specifically define it. 32 is a battery or any other generator of electric current. The telephone 31 and the battery 32 are electrically connected in series with each other and with the primary coil 30.

The filament 14, of the triode 10, has one of its terminals electrically connected to one of the terminals of the filament 14, of the triode 11. The other terminal of filament 14, of triode 10, is electrically connected to one terminal of the rheostat 15. The other terminal of filament 14, of triode 11, is electrically connected to one terminal of the rheostat 17. A battery, or other generator of electric current, 19, has its negative terminal electrically connected to the common terminal of the filaments 14. The positive terminal of the battery 19 is electrically connected to the rheostats 15 and 17 by means of the switches 16 and 18 respectively. The negative terminal of the battery 19 is also electrically connected to the negative terminal, 34, of a battery, or other generator of electric current, 24. An inductance coil 26 is electrically connected in series between the positive terminal of the battery 24 and the common terminal 33 of the inductance coils 3 and 5. A variable condenser 27 is electrically connected in parallel with the inductance coil 26. A condenser 25 is electrically connected in parallel with the battery 24. A condenser 35 and inductance coil 20 are electrically connected in series, between the grid 13, of the triode 10, and the terminal 34 of the battery 24. A switch 36 is electrically connected in parallel with the condenser 35. A condenser 37 and an inductance coil 22 are electrically connected in series between the grid 13, of the triode 11, and the terminal 34 of the battery 24. A switch 38 is electrically connected in parallel with the condenser 37. The inductance coils 20 and 22 have cores 21 and 23 respectively, preferably of iron, or steel, of laminated structure. Coils 20 and 22 should each have sufficient impedance to reduce radio frequency currents which might otherwise be established therein to a negligible value. I have found it to be entirely satis-

factory to provide coils 20 and 22 each having impedance substantially equivalent to that of each of the triodes 10 and 11 (between plate and filament) at all radio frequencies commonly employed. The secondary coil 28 should have impedance of approximately the same value as that of each of the coils 20 and 22. The condensers 35 and 37 should be of equal capacitance, the value of which may be established within a relatively wide range of values. Condensers 35 and 37 each of one microfarad capacitance have been found to be satisfactory. Condenser 25 may vary in capacitance within a wide range of values. I have found a condenser 25 of 0.5 microfarads 80 capacitance to be suitable for the purpose of this invention when using a variable condenser 27 having a maximum capacitance of 0.005 microfarads. An inductance coil 26 of 14 millihenrys, direct current resistance of 10 ohms, and negligible capacitance has been found to be satisfactory when used in connection with a variable condenser 27 having maximum capacitance of 0.005 microfarads. I have found it possible to substitute fixed condensers for the variable condensers 8 and 9, each fixed condenser having approximately 0.001 microfarads capacitance. I prefer however to use variable condensers 8 and 9 each having a maximum capacitance of 0.001 95 microfarads. The difference of potential generated between the terminals of the battery 24 together with the temperature of the filaments 14 should be fixed at values largely established by the structural parameters of 100 the triodes 10 and 11. The triodes 10 and 11, should be so constructed, with respect to kind and relative spacing of their electrodes as to render them suitable for operation under conditions established by the power represented 105 by the electro-magnetic waves generated by my transmitting system. With this end in view the design and construction of the triodes may accord with well known principles governing the construction of triodes in general; as I have determined by using triodes designed for use in connection with other well known systems of approximately the same power out-put value as that involved in my experiments. The difference of potential generated between the terminals of the battery 32 should be limited to that suitable for most efficient operation of the telephone 31, or of such other device as may be used in place thereof.

In the operation of this arrangement of circuits the rheostats 15 and 17 should be adjusted, by means of the switches 16 and 18 respectively, to establish a current in each of the filaments 14, of the triodes 10 and 11, just sufficient to fix the temperature of the filaments at a value suitable for the best operation of the triodes with respect to the power represented by the electro-magnetic waves to be generated. If maximum power out- 130

put is desired the switches 36 and 38 should be closed, thereby short-circuiting the condensers 35 and 37 respectively. The switches 2 and 4 and the condenser 6 should be adjusted to render the circuit 5 1—2—3—5—4—6—7 resonant at the frequency of the current desired therein, as established by the wave length of the electro-magnetic waves to be generated. The condenser 10 27 should be adjusted to render the compound circuit which includes the battery 24 and condenser 25 (in parallel); the coil 26 and condenser 27 (in parallel); the coil 3, switch 2 and plate 12, of triode 11, in parallel with the coil 5, switch 4 and plate 12, of triode 10; the filaments of the triodes 10 and 11 through their common terminal to the terminal 34 of the battery 24; resonant at substantially twice the resonant frequency of the circuit 15 1—2—3—5—4—6—7. (Reference is made to my herein-before mentioned prior Patent Number 1,507,689 for more extended discussion of the principles involved in the relative adjustments of the constants of similar circuits for the production of radio frequency currents, or the maximum re-inforcement of such currents.) The switch 40 should be opened. Current impulses will now be established from the battery 24 through the 20 30 condenser 27 to the common terminal 33 of the coils 3 and 5. These impulses will alternately find a path through the coils 3 and 5, in the manner which I have described in my herein-before mentioned Patent Number 1,507,689, and will constitute, in part, an alternating current in the circuit 1—2—3—5—4—6—7 of the frequency to which that circuit is resonant. I shall designate this current as the "radio frequency current." As is well known, a part of the 25 35 energy represented by the radio frequency current is converted into energy in the form of radiated electro-magnetic waves. It is also well known that variations in either the frequency or in the amplitude of the radio frequency current will produce like variations in the length or amplitude, respectively, of the electro-magnetic waves. In the present invention I have provided means of 40 45 varying the amplitude of the radiated electro-magnetic waves either by partially modulating such amplitude, as is the case when speech is transmitted telephonically, or by intermittently or periodically interrupting the continuity of the wave stream and thereby producing trains of waves of various train lengths, which may constitute telegraphic signals.

I have explained, in my patent herein-before referred to, the manner in which a radio frequency current may be established, reinforced, or indefinitely maintained in an oscillatory circuit, similar to the present circuit 1—2—3—5—4—6—7, wherein there is 45 50 an analogous association of triodes with the

circuit discussed. In the present invention the radio frequency current likewise is produced and thereafter sustained by the alternate opening and closing of the plate to filament paths in the triodes 10 and 11, since the conductivity of these paths is a function of the electrical potential of the grids 13 with respect to the filaments 14 and the current therein is also a function of the electrical potential of the plates 12 with respect to the filaments 14, considering that the electrical differences of potential mentioned are produced by, and have the same period as, the radio frequency differences of potential between the points in the circuit 1—2—3—5—4—6—7 with which the grids 13 are electrically connected.

From the preceding description it will be seen that the valves 10 and 11, with their associated circuits, may be aptly designated as being in reciprocative association; as such provides means for producing and, thereafter, directly sustaining and reinforcing an alternating current by a reciprocating action. More specifically, the means mentioned consists, in part of two electron valves so arranged, electrically, with respect to their associated circuits, as to permit the passage of a directly sustaining, or reinforcing, current between the cathode and anode of each respective valve, only during alternate periods of time, the control members and anodes of the said valves being so associated with an oscillatory circuit, in which said alternating current is resident and, in part wherein, said directly sustaining or reinforcing, current is also resident in the form of a pulsating current, as to determine, and limit, the time periods of maximum conductivity of each valve alternately; the said time periods with respect to one of said valves, being limited to the time periods of the positive half cycles of said alternating current in said oscillatory circuit, and, with respect to the other of said valves, to the time periods of the negative half cycles of the said alternating current. In this arrangement of the valves, and circuits, each positive pulse of the directly sustaining, or reinforcing, current directly reinforces one, and one only, half cycle of the said alternating current, and each of said half cycles is, in this way, reinforced. I shall hereinafter, in the claims, designate the means herein described, as "electron valves in reciprocative association".

It is to be noted that the pulses of current, supplied by the battery 24, are effective in reinforcing, and thereby sustaining, the radio frequency current in circuit 1—2—3—5—4—6—7 in proportion to their amplitude and to their agreement in phase with the radio frequency current. If these pulses of current are caused to pass, in their entirety, alternately through coils 3 and 5 and in phase with the radio frequency current simultane-

ously existent in the coil through which they pass, there will, for a given pulse amplitude, be maximum reinforcement of the radio frequency current. To fully accomplish this result it is requisite that the plate to filament paths of the triodes 10 and 11 shall alternately open and entirely close. It is evident that the greater the difference between the conductivity of the plate to filament path of the triode which is open and that of the same path in the triode which may be but partially closed, at the moment of maximum pulse, the more nearly will the result discussed be approximated. It is known that the conductivity of the plate to filament path of a triode increases, within certain limits, as the electrical potential of the grid becomes more positive with respect to the filament of the triode, and, conversely, decreases as the grid becomes more negative in its electrical potential with respect to the filament. In the drawing, Fig. 1, it may be clearly seen that there can be no appreciable difference of electrical potential between the filaments, 14, of the triodes 10 and 11, as these filaments are electrically connected together having one terminal common to both of them. Variations, therefore, in the difference of electrical potential between the grid 13, of the triode 10, and the grid 13, of the triode 11, will react upon the alternating conductivities of the plate to filament paths of the triodes and consequently, upon the degree of reinforcement, by the pulses of current supplied by the battery 24, of the radio frequency current in the circuit 1—2—3—5—4—6—7. Variations of electrical potential difference between the grids 13, of the triodes 10 and 11, will in the manner explained therefore produce proportional variations in the amplitudes of the radio frequency current in the circuit 1—2—3—5—4—6—7 and in the energy represented by the electro-magnetic waves radiated by that circuit.

If it is desired to transmit speech, or other sounds, sound waves impressed upon the diaphragm of the telephone 31 will cause variations of electric current in the primary coil 30, as is well known; these variations will, by means of the inductive association of the coil 30 with the secondary coil 28, produce alternating potential differences, between the terminals of the latter coil, of the same frequency as that of the sound waves; these potential differences will establish an electric current having two principal components, one of which will reside in the circuit 28—36—20—22—38 and the other alternately in the circuit 28—triode 10, (grid 13 to filament 14) 22—38 and in the circuit 28—triodes 11 (grid 13 to filament 14) 20—36. The latter component alternates between the two last defined circuits, due to the uni-directional conducting property of the grid to filament paths of the triodes, at the voice, or audio, fre-

quency of the current. Due to the combined effect of these audio frequency currents, there is impressed between the grids 13, of the triodes 10 and 11, variations of differences of electrical potential of the same frequencies and of proportionate amplitudes. These variations of electrical potential cause like variations in the energy represented by the radiated electro-magnetic waves in the manner hereinbefore described.

If it is desired to transmit by telegraph, the signals consisting of long and short groups of wave trains, a key operated buzzer, or other similar device, may be substituted for the telephone 31. The phenomena appertaining to this method of operation is the same as that described in connection with the transmission of sound, except that the sound frequency modulations are replaced by the frequency of interruption of the current, in the primary coil 30, as caused by the action of the buzzer, during the periods in which it is active, as determined by the manipulation of its controlling key.

If it is desired to transmit by telegraph, the signals consisting of uninterrupted wave trains of various lengths, the switch 40 should be closed. The grids 13 are now electrically connected to each other by means of the closed switch 40 and the key switch 39, which is in its normal, closed, position, and there is negligible difference of electrical potential between them. Under this condition there will be no appreciable reinforcement of the radio frequency current, in the circuit 1—2—3—5—4—6—7, and it will immediately cease. If now the key switch 39 be depressed it will open the low impedance electrical connection between the grids, introducing the high impedance coil 28 in place thereof, and the radio frequency current, above mentioned, will be re-established. Signals may, therefore, be transmitted of the desired kind by manipulating the key switch 39.

I have found it possible to operate my present arrangement of circuits in all of the ways herein-before described, but at greatly reduced power output, by opening the switches 36 and 38 and thereby introducing the condensers 35 and 37 respectively into the previously described circuits in place of the switches mentioned. Condensers 35 and 37, when introduced into the circuits in the manner shown, become reservoirs, or traps, tending to check that component of the audio frequency current which finds a circuit alternately between the grid and filament of triode 10 and the grid and filament of triode 11, as herein-before described. I have found the introduction of condensers 35 and 37 into the circuits, as shown, to be desirable for the purpose of reduction of the power represented by the radiated electro-magnetic waves. It may be readily understood that the introduction of these condensers, in the manner shown

and described, lowers the effective reactance between the grids 13 and therefore limits the maximum difference of electrical potential between them and, consequently, limits the degree of reinforcement of the radio frequency current possible when they are so introduced.

5 I have found it to be possible to operate my present arrangement of circuits, modified by the removal of condensers 35 and 37, the switches 36 and 38, and the coils 20 and 22; but only at greatly reduced power. In the latter instance there is no audio frequency current produced by the audio frequency potentials at the terminals of the secondary coil 28. These potentials are, however, impressed between the grids 13 and cause modulations in the radio frequency current as hereinbefore described. The radio frequency current 10 is limited in its amplitude by the effect of charges retained by the condensers 8 and 9 due to the uni-directional conducting property of the triode grid to filament paths; such charges operating to reduce the difference of 15 potential between the grids.

20 Referring to Fig. 2, 1 represents the ordinary elevated part of an antenna, at a radio transmitting station, which is electrically connected in series with the switch 42, the inductance coil 41, to the ground, or counterpoise, 25 7. The variable condenser 43 has its terminals electrically connected to the switches 2 and 4 respectively. The inductance coil 41 is in variable inductive association with the inductance coil 3. The remainder of this figure is the same as that of Fig. 1.

30 In the operation of this arrangement of circuits the same methods are employed and the same phenomena are created thereby as those described in connection with Fig. 1; except that it is necessary to adjust the circuits 1—42—41—7 and 2—3—5—4—43 both to a condition of resonance at the frequency of the radio frequency current desired. This 35 condition is attained by adjusting the switches 42, 2 and 4, the condenser 43 and the coupling between the coils 41 and 3.

40 It is obvious that many other modifications, or changes, in the shape, kind and arrangement of the various parts may be made without departing from the broad scope of the appended claims. As an example, it is clear that the action herein described may be obtained by substituting one electron tube having a single filament, two grids and two plates for the triodes 10 and 11. It may also be seen that other electric valves operating in a manner similar to the triodes may be used. It is further apparent that my arrangement 45 of circuits and combinations of electrical apparatus may be used for many purposes, wherein modulation, or interruption, of an alternating electric current is desired, other than those described herein. While I have shown various forms and kinds of apparatus

as included in the elementary parts of my arrangement of circuits, I do not desire to be limited, or restricted, in the broad scope of my invention, as described in the claims, to any specific structure of apparatus or its arrangement in elementary circuits, the assemblage of which forms the means of accomplishing the purposes herein-before stated in substantially the manner herein described.

70 Having set forth the object and nature of my invention, and various means and arrangements of accomplishing the purpose thereof, what I claim as new and useful, and of my own invention, and desire to secure by Letters Patent is:—

75 1. The combination with a converter of electric current embodying two electron valves in reciprocative association arranged to convert direct current into a single alternating current only, of modulating means connected with the respective control members of said two valves and arranged to modulate converted electric current by impressing electric potential differences between said two control members and electric circuits, provided with grouped inductance, external to said electron valves and external to the source of said modulating potentials affording means for the passage of electric currents produced by said electric potential differences.

80 2. The combination with a converter of electric current embodying two electron valves in reciprocative association arranged to convert direct current into a single alternating current only, of means for modulating the converted current from said converter by the application of external forces, said means including devices for impressing electric potential differences produced by said external forces between the respective control members of said two electron valves and circuits, having grouped inductance external to the source of said modulating potentials and grouped capacitance external to said electron valves affording means for the passage of electric currents produced by said electric potential differences.

85 3. A system for generating a one-frequency alternating current modulated at lower frequency comprising an oscillatory circuit, a 90 source of direct current connected thereto through a pair of readily variable resistance gaps responsive to both frequencies, resistance influencing means associated with said gaps, said means being so excited by 95 current flow in said circuit as to influence said gaps oppositely whereby alternating currents are generated in said circuit, and a source of lower frequency modulating current connected directly to said gap influencing 100 means to also excite said influencing means oppositely.

105 4. A system for generating a one-frequency alternating current modulated at lower frequency comprising an oscillatory circuit, a 110

- source of direct current connected thereto through the filament-to-plate paths of a pair of three-electrode vacuum tubes connected in parallel relation to opposite sides of a reactance element in said circuit, reactance means connecting the grid electrodes of said tubes to opposite sides of said reactance element in said circuit, and a source of lower frequency modulating current connected to said grid electrodes.
5. A system for generating a one-frequency alternating current modulated at lower frequency comprising an oscillator circuit having a pair of substantially equally reacting inductance coils non-inductively related and a condenser, a source of direct current connected to said circuit at a point between said coils and to opposite sides of said condenser by way of the filament-to-plate paths of a 15 pair of three electrode vacuum tubes, reactance means connecting the grid electrodes of said tubes to said oscillating circuit at opposite sides of said condenser, and a source of lower frequency modulating current connected between said grid electrodes.
- 20 6. A system for generating a one-frequency alternating current modulated at lower frequency comprising an oscillatory circuit, a source of direct current connected thereto through a pair of readily variable resistance gaps responsively sensitive to both frequencies, means for influencing the resistance of said gaps intimately associated therewith, reactance means directly connecting said gap 25 influencing means to said oscillatory circuit, so that the influencing means are excited by current flow in said circuit in a direction so as to influence said gaps oppositely whereby current flow from said direct current source 30 is commutated to create alternating currents in said oscillatory circuit, and means directly connected to said gap influencing means for simultaneously applying lower frequency modulating current effects directly to said 35 gap influencing means for additionally influencing the resistance of said gaps.
